UNITED STATES PATENT OFFICE.

FREDERICK S. DENISON, OF MINNEAPOLIS, MINNESOTA, ASSIGNOR TO MINNEAPOLIS
HEAT REGULATOR COMPANY, OF MINNEAPOLIS, MINNESOTA, A CORPORATION.

ALARM-CLOCK.

1,254,212.

Specification of Letters Patent. Patented Jan. 22, 1918.

Application filed December 17, 1915. Serial No. 67,385.

To all whom it may concern:

Be it known that I, FREDERICK S. DENISON, citizen of the United States, resident of Minneapolis, county of Hennepin, State of Minnesota, have invented certain new and useful Improvements in Alarm-Clocks, of which the following is a specification.

Alarm clocks as usually constructed are provided with a release or trip for the alarm operating at a predetermined time, being reset for operation at a subsequent time.

The object of my invention is to provide a clock having an alarm attachment which will operate to sound the alarm at predetermined intervals with one winding for a period corresponding preferably to the length of time for which the clock main spring is wound. That is, if the clock requires winding once in eight days, then the alarm attachment will run for eight days, sounding the alarm for a certain indicated time, or at definite periods each day without further attention.

A further object is to provide an alarm mechanism which may be used in connection with a thermostatic heat regulator.

Other objects of the invention will appear from the following detailed description.

The invention consists generally in various constructions and combinations, all as hereinafter described and particularly pointed out in the claims.

In the accompanying drawings forming part of this specification,

Figure 1 is a front view of an alarm clock with the face removed,

Fig. 2 is a sectional view on the line $x-x$ of Fig. 3,

Fig. 3 is a vertical sectional view through the clock, showing the operating mechanism therefor,

Fig. 4 is a detail sectional view, showing one position of the alarm mechanism.

Fig. 5 is a similar view, showing another position of the alarm,

Fig. 6 is a detail sectional view, showing the manner of mounting the operating spring of the alarm,

Fig. 7 is a similar view, showing the adjusting mechanism by means of which the period of operation of the alarm is controlled,

Fig. 8 is a detail sectional view, showing

the post of the indicator hands and its connection with the clock main spring,

Fig. 9 is a view of the alarm dial and the hands for indicating the desired period of operation of the alarm.

In the drawing, 2 represents the casing of a clock, having the usual glass face 3 and dial plate 4. 5 represents a post mounted in the front and rear plates 6 and 7 of the clock frame and having a hub 8 mounted on one end thereof and provided with a gear 9 which meshes with a pinion 10 on a gear 11 that is supported by a plate 6 and meshes with a pinion 12 that is secured to the post 5. The hub 8 has a pinion 13 secured thereon, and said hub also has a seat for the hour hand 14, the minute hand 15 being mounted on the projecting end of the post 5. A hub 16 is secured on the post 5 between the plates 6 and 7. A pinion 17 has its hub in frictional engagement with the hub 16 and is provided with a gear 18 between which and a collar 19 on said post a spring plate 20 is inserted, and having sufficient tension to hold the pinion 17 and the hub 16 together with sufficient pressure to revolve the hub 16 and the post 5 with said pinion, but allowing said post to be rotated independently of the pinion 17 for the purpose of setting the clock hands.

A post 21 is mounted in the plates 6 and 7, parallel with the post 5, and the clock main spring 22 is secured at one end thereto and at its opposite end to a drum 23 that is provided with teeth 24 at one end to mesh with the teeth of the pinion 17 and drive said pinion. A ratchet wheel 25 is mounted on the post 21, and provided with a dog 26 which engages the teeth of the ratchet. The post 21 has the usual squared end to receive the shank of the winding key. The gear 18 is connected to a train of gears 26^a with an escapement 27 and balance wheel 28, all of ordinary construction.

I will now proceed to describe in detail the alarm attachment of the clock and to which my invention particularly relates. 29 is a post, fitting within a sleeve 30 that is journaled in the plates 6 and 7. A gear 31 is formed on the sleeve 30 to revolve therewith and a drum 32 is seated against said gear and is provided with a hub 33 journaled on the post 29 and on which hub a ratchet 34 is mounted, being secured by a pin 35

which passes through the ratchet, the hub and said post. A dog 36 is mounted on the clock frame for engaging the teeth of the ratchet. A spring 37 is secured at one end 5 to the sleeve 30 and at its other end to the drum 32 and when the post 29 is revolved, the spring will be wound from the outside, the drum 32 revolving with the post. As indicated by dotted lines, a crank may be 10 mounted on one end of the sleeve 30 for the purpose of tripping or shifting some independent mechanism, such as the contact posts of a thermostat (not shown). The gear 31 meshes with a pinion of a gear 38 15 which in turn drives a pinion 39 having an escapement 40. A post 41 carries the pallet 41' of the escapement.

A hammer 42 is mounted on said post and vibrates therewith when the alarm is released 20 to intermittently contact with the gong 43 that is secured to the rear face of the clock. An arm 44 is mounted in the post 41 and projects outwardly therefrom, parallel substantially with the gong hammer. 25 A spring 45 is secured at one end to the plate 6 and extends across said plate in a plane parallel substantially therewith and is provided with a pin 46 which projects through said plate into the path of the arm 44, and normally prevents operation of the alarm device. A sleeve 47 is mounted in 30 the frame of the clock and is provided with a shoulder 48 held against the plate 7 by the tension of a disk 49 that is mounted on said sleeve and has a bearing on the plate 6. The sleeve 47 has a flat surface 50 whereon the hub of an annular flange 51 is mounted, said flange having a peripheral notch 52 formed therein, and provided with an 35 inclined or cam surface.

The spring 45 has an opening 53 therein to receive the sleeve 47 and the hub of the flange 51, and the tension of said spring normally forces said hub outwardly on said 45 sleeve. A post 54 is mounted in said sleeve and is provided with an annular rib 55 against which the sleeve 47 is seated, and a gear 56 is loosely mounted on said post and is provided with a pin 57 to bear on the edge 50 of the flange 51. A flange 58 has its hub fixed on the post 54 and is provided with a peripheral notch 59 having an inclined surface corresponding to the one described with reference to the flange 51, the edge of said flange 58 being in position on the opposite side of the gear wheel 56 from the flange 51 to contact with the opposite end of the pin 57.

The end of the post 54 is mounted in a 60 plate 60 that is carried by the frame of the clock and a spring disk 61 is mounted on said post and is seated on said plate with sufficient pressure to hold the parts against premature movement. The opposite ends 65 of the sleeve 47 and the post 54 project

through a dial 62 that is graduated to indicate the hours of the day, and also preferably has the "A. M." and "P. M." letters thereon.

The end of the sleeve 47 is exteriorly 70 threaded and provided with a finger grip 63 and a lock nut 64 for securing it on the sleeve, an indicator hand 65 being interposed between the finger grip 63 and a shoulder on the sleeve. 75

The outer end of the post 54 is exteriorly threaded to receive a finger grip 66 and a lock nut 67, a hand 68 being secured between the finger grip 66 and a shoulder formed on the post. This construction permits the 80 sleeve and the post to be revolved independently of one another for the purpose of setting the indicator hands opposite the desired figures on the dial.

The gear 56 meshes with the wide faced 85 pinion 13 (see Figs. 7 and 8) and is revolved thereby, independently of the sleeve 47 and the post 54 during the normal operation of the time piece. As this gear revolves, the pin 57 will slide on the peripheries of the 90 flanges 51 and 52 and at a predetermined point in its travel will drop into the notch in one of these flanges. If the sleeve 47 should be set in the position to allow the pin to drop into the notch in the flange 51, 95 the spring 45 would immediately be released and slide the flange 51 outwardly on the spring 45 and withdraw the pin 46 from its locking position with respect to the arm 44 and permit the alarm mechanism to 100 operate and the hammer to vibrate and ring the gong.

If the flange 58 should be set in position so that its recess 59 would first receive the pin 57, then the pressure of the spring 45 105 would slide the flange 51 and the gear 56 outwardly on the post 54, the face of the pinion 13 being sufficiently wide to allow the gear 56 to slide back and forth on the post 54 and still remain in mesh with the 110 teeth of the pinion.

The flanges 51 and 58 may be revolved independently of one another through the rotation of the sleeve 47 and the post 54 and consequently the notches in these flanges 115 may be located in different positions with respect to one another to vary the period of release of the spring 45 and the alarm mechanism and also change the interval between these periods. The alarm mechanism 120 and release provides for two operations in twenty-four hours, and adjustment of the indicator hands permitting any desired interval between the operations, and, if desired, the indicator hands may be adjusted 125 directly opposite one another, so that the notches in the flanges 51 and 58 will register with one another and the pin 57 will drop into one of these notches and permit a single 130 operation of the alarm.

A bar 69 has a slot 70 therein to receive a pin 71 on the plate 7 and also has a slot 72 to receive a guide pin 73 on said plate. The bar 69 has an inwardly turned end portion 74 that is adapted to move into the path of the arm 44 and a lug 75 is mounted on said bar in position to be engaged by a similar lug 76 on the gear 31. A pin 77 is mounted in the spring 45 and slideable in the plate 6 10 and a guide 78 and engages the bar 69 and normally holds it outwardly against the tension of a spring 79, so that the lug 75 will be out of the path of the lug 76 and a spring 80 is mounted to engage one end of the bar 15 69 and hold it at the limit of its longitudinal movement in one direction, the bar sliding on the pins 71 and 73 to the ends of the slot 72.

When the pressure of the pin 77 is withdrawn by the release of the spring 45, the 20 spring 79 will move the bar 69 inwardly and the lug 76, engaging the lug 75, will move said bar lengthwise against the tension of the spring 80 until the end 74 is in the path of the arm 44 to arrest the vibration thereof and check the alarm.

I prefer to provide two of the lugs 76 upon opposite sides of the center of the gear wheel 31, so that the bar 69 will be operated 30 twice with each complete revolution of the gear. As shown in Fig. 5, the pin 57 will have entered one of the notches and will begin to climb the inclined face thereof about the time that one of the lugs 76 engages the lug 75 to move the bar 69 and the end 74 into the path of the vibrating arm 44.

During the interval between the entrance of the pin 57 into one of the notches and the adjustment of the end 74, the gong 40 will be vibrated to ring the alarm. As soon as the end 74 engages the vibrating arm, the alarm will be checked and as the pin 57 rides up the inclined face of a flange, the spring 45 will be pressed inwardly and the 45 pin 77, engaging the bar 69, will force it outwardly and disengage the lugs 75 and 76, and the spring 80 will move the bar lengthwise sufficiently to disengage the end 74 from the vibrating arm and at the same time the 50 pin 46 will move into the path of said arm and check further vibration thereof until the spring 45 is again released.

It is evident that the indicator hands may be set any desired distance apart, so that 55 the pin 57 may drop into one notch and release the alarm and then, after a desired interval, drop into the opposite notch and again release the alarm without the necessity of winding the alarm or setting it after 60 the first operation. The alarm will be operated for a brief period only and under normal conditions will run for the same period as the time piece does.

As heretofore intimated, if desired the 65 notched flanges may be set directly opposite

one another, so that only one operation of the alarm will occur during the complete revolution of the clock hands.

In various ways the details of construction herein shown and described may be modified and still be within the scope of my invention.

I claim as my invention:

1. An alarm clock comprising a time mechanism, an alarm attachment including 75 a gear driven from said time mechanism, a pin mounted therein, flanges disposed upon opposite sides of said gear and having notches therein and cam surfaces to receive said pin at predetermined intervals, and 80 means becoming operative when said pin enters either of said notches to release said alarm attachment.

2. A clock comprising a time mechanism, an alarm attachment, a gear driven by said 85 time mechanism, means having cam surfaces mounted at opposite sides of the said gear for relative movement with respect to said gear, and a device having means for normally checking the operation of said alarm 90 attachment but releasing it at predetermined times through the relative movement of said gear and said cam surface means.

3. An alarm clock comprising a time mechanism, an alarm attachment having a 95 vibratable hammer and arm extending from the shaft of the hammer, a drum containing a spring and connected by a train of gears with the shaft of the hammer to vibrate the hammer, a slideable spring influenced bar 100 having a part positioned to be brought into the path of movement of the arm of the hammer shaft, projections on said bar and the spring drum, respectively, and means for bringing said projections into engagement with each other at a predetermined time to shift the bar and bring it into the path of movement of the arm of the hammer shaft to check the vibration of the 105 hammer.

4. An alarm clock comprising a time mechanism, an alarm attachment including a vibratable hammer, concentric members revoluble independently of each other, indicator hands mounted on said members, a 115 dial, a continuously rotatable gear mounted to freely revolve on one of said members and driven from the time mechanism, alarm setting devices associated one with each of said concentrically disposed members and coacting with said continuously rotating gear to fix a predetermined time for sounding the alarm, and a spring carrying a member to control the movement of the vibratable hammer and connected with the alarm setting 120 devices to be under the control thereof.

5. An alarm clock comprising a time mechanism, an alarm attachment including a vibratable hammer, concentric members revoluble independently of each other, indi- 130

cator hands mounted on said members, a dial, a gear mounted to freely revolve on one of said members, alarm setting devices associated one with each of said concentrically disposed members and coacting with said gear to fix a predetermined time for sounding the alarm, a member carrying a part to control the movement of the vibratable hammer and connected with the alarm setting devices to be under the control there- of, a second hammer controlling member, and means for rendering said second mentioned member active to restrain the movement of the vibratable hammer when free from restraint by the first mentioned controlling member. 15

In witness whereof, I have hereunto set my hand this 11th day of December 1915.

FREDERICK S. DENISON.
